UNITED STATES PATENT OFFICE.

WILLIAM F. ERICKSON AND HANS D. BOLSTAD, OF STARBUCK, MINNESOTA.

SHAVING KIT.

1,274,153.

Specification of Letters Patent. Patented July 30, 1918.

Application filed September 6, 1917. Serial No. 190,070.

To all whom it may concern:

Be it known that we, WILLIAM F. ERICKSON and HANS D. BOLSTAD, citizens of the United States of America, residing at Starbuck, in the county of Pope, and State of Minnesota, have invented certain useful Improvements in Shaving Kits, of which the following is a specification, reference being had therein to the accompanying drawing.

10 This invention has reference generally to improvements in that class of inventions known as toilet articles and more particularly relates to shaving kits.

As the primary aim and object this invention contemplates the provision of a device of the above character designed to receive a plurality of shaving articles so that they may be conveniently carried therein, the device itself being particularly suited for the convenience of travelers.

15 It is an equally important object of this invention to provide a shaving kit wherein the cover is constructed in sections and designed to support a mirror which is arranged so as to be supported in various positions of adjustment.

20 More particularly the present invention embraces the provision of a foldable sectional cover for a shaving kit and which is designed to entirely close the kit when in a folded position and support a mirror when in an extended position.

25 Among the other aims and objects of this invention may be recited the provision of a device of the character described with a view to compactness, and in which the number of parts are few, the construction simple, the cost of production low and the efficiency high.

30 Other improvements and novel details in the construction and arrangement of the various parts of the apparatus will be brought out more in detail in the description to follow, which for a clear understanding of the invention should be considered in connection with the accompanying drawings forming a part hereof, and wherein is disclosed for the purpose illustration, a convenient and satisfactory embodiment of the invention.

35 It is to be noted in this connection that minor changes in the construction and arrangement of parts may be made without

departing from the principle of operation of the various parts.

The invention is clearly illustrated in the accompanying drawings, in which:

Figure 1 is a perspective view of the device in a closed position;

Fig. 2 is a perspective view of the device in an open position; the cover being extended;

Fig. 3 is a longitudinal section of the invention in a closed position;

Fig. 4 is a transverse section of the same.

Similar characters of reference are employed in all the above described views, to indicate corresponding parts.

Referring now, more particularly, to the accompanying drawings, there is provided a receptacle designated in its entirety by the numeral 1 consisting of a bottom 2, side walls 3, a front wall 4 and a rear wall 5 on the upper edge of which is formed an extension 6 for a purpose that will presently appear. A transverse partition 7 is arranged between side walls adjacent the front wall forming a compartment 8 which is adapted to receive a folded strop and likewise another transverse partition 9 is mounted between the side walls adjacent the rear wall and co-operates with a short longitudinal partition 10 in providing compartments 11 which are adapted for receiving soap and a collapsible cup or the like. A pair of relatively long longitudinal partitions 12 are mounted between the transverse partitions 7 and 9 adjacent the side walls 3 providing razor receiving compartments 13 and a brush receiving compartment 14.

With a view toward providing improved closing means for the receptacle, the improved foldable sectional cover designated in its entirety by the numeral 15 is employed. This cover consists of an inner section 16 pivoted through the instrumentality of hinges 17 to the upper edge of the extension 6 on the rear wall, the outer edge thereof being designed to terminate short of the front wall for a purpose that will become apparent. The outer section 18 of the cover has one surface adjacent one end reduced forming a transverse shoulder 19 at which point it is pivoted to the outer end of the other section through the instrumen-

tality of hinges 20 while the opposite surface is designed to support a mirror 21. By this arrangement it will be appreciated that the sections 16 and 18 when folded in superposed relation with each other as indicated in Fig. 3 and when resting on the upper edges of the side walls and the front wall form a complete closure for the receptacle 1 whereas on the other hand when the section 10 16 is swung upwardly and the section 18 swung outwardly so that the inner edge engages the upper edges of the side wall, the mirror 21 carried by the inner face of this section is capable of being supported in various positions of adjustment for the convenience of the owner.

In actual practice the receptacle and cover may be plush covered and lined while suitable catch means such as indicated by the 20 numeral 22 may be mounted on the outer end of the section 18 in the adjacent front wall for removably holding the sectional cover in a folded position so as to entirely close the receptacle and prevent accidental 25 displacement of the contents.

In view of the foregoing description it is thought that a further detail description of the operation of the invention is entirely unnecessary. Likewise it is believed that 30 the advantages of the invention will be readily apparent.

As many changes could be made in the above construction and many apparently widely different embodiments of this invention could be made without departing from the scope thereof, and it is intended that all matter contained in the above description or shown in the accompanying drawings shall be interpreted as illustrative and 35 not in a limited sense. It is also to be understood that the language used in the following claims is intended to cover all the generic and specific features of the invention herein described and all statements of the 40 scope of the invention which, as a matter of language might be said to fall therebetween.

Having thus described this invention,

what is claimed as new and desired to be secured by Letters-Patent, is:—

1. A device of the character described including a receptacle provided with a plurality of receiving compartments, a sectional cover embodying two sections one of which is pivoted to the inner end of the receptacle and terminates short of the other end, while the other section is pivoted at a point adjacent its outer end to the outer end of the first section and is foldable to intimately contact with the inner face of the first section to coöperate with the first section in completely closing the receptacle and upon the raising of the first section is swingable outwardly so as to be supported in various positions of adjustment upon the upper edges of the receptacle and be braced by the first section, and a mirror carried by the last section.

2. A device of the character described including a receptacle provided with a plurality of compartments adapted to receive articles, an extension formed on the rear wall of the receptacle, a foldable sectional cover composed of two sections, one of the sections being pivotally connected to the extension and terminating short of the front wall of the receptacle, the other section being reduced on one surface adjacent one end to provide a transverse shoulder, means for pivotally connecting the second section at a point adjacent the shoulder to the outer end of the first section to permit of the arrangement of the sections in superposed relation on the upper edge of the receptacle to completely close the receptacle and to permit of the swinging of the second section 85 outwardly so as to be supported at various inclinations on the upper edge of the receptacle by the first section, and a mirror carried by the opposite face of the second section.

In testimony whereof we affix our signatures.

WILLIAM F. ERICKSON.
HANS D. BOLSTAD.
